**OLEFIN PYROLYSIS PROCESS PROMOTED
WITH MIXTURES OF BROMINE AND ARO-
MATIC HYDROCARBONS**

Kenneth J. Frech, Tallmadge, Ohio, assignor to The Goodyear Tire & Rubber Company, Akron, Ohio, a corporation of Ohio
No Drawing. Continuation-in-part of application Ser. No. 399,068, Sept. 24, 1964. This application Aug. 17, 1966, Ser. No. 572,905

10 Claims. (Cl. 260—680)

ABSTRACT OF THE DISCLOSURE

Olefins are cracked using as the cracking promotor a mixture of a bromine containing compound and benzene, toluene or xylene. Increased yields and efficiencies are shown for the preparation of isoprene from 3-methyl-2-pentene by the use of hydrogen bromide with benzene and toluene as the cracking promotor.

This application is a continuation-in-part of Ser. No. 399,068, filed Sept. 24, 1964 which was, in turn a continuation of Ser. No. 218,169, filed Aug. 20, 1962, all of which are now abandoned.

This invention relates to an improved process of olefin pyrolysis employing certain materials as pyrolysis promoters.

It is known that certain olefins may be thermally decomposed or cracked by subjecting them to elevated temperatures, for instance olefins which have in their molecular make-up a carbon-carbon bond which is in a position beta to the double bond will, under proper conditions of heat, time and pressure, undergo a scission of the carbon-carbon bond in the position beta to the double bond. By the terms "cracking," "decomposing," "cracked," or "decomposed" as employed throughout this specification and claims is meant that the olefin molecule splits into two or more fragments at the carbon-carbon bond which is in a position beta to the double bond. This will be explained in more detail later.

The thermal decomposition or cracking of olefins is usually conducted in a closed zone or reactor and is usually conducted in the absence of oxygen. The temperatures employed usually vary from about 300 to about 1,000° C. Usually this thermal cracking process is conducted while the olefins are in a gaseous state. The olefins may be cracked in relatively pure form or a diluent may be employed.

Employing the most favorable conditions conducive to the cracking of olefins, these conditions being temperature, residence time in the cracking zone, the ratio of the olefin to the diluent if any be employed, it has been found that olefins decompose in fairly low yields and at fairly low efficiency. As employed in this application the term "yield" is meant to connote the decomposition of the olefin feed stock per pass through the cracking zone and the term "efficiency" is meant to connote the total decomposition to the desired end product when employing conventional recycle techniques.

It is therefore the object of this invention to provide a method whereby the per pass yield of the desired products produced by cracking these olefins is increased. Another object is to increase the ultimate yield or efficiency of the desired product. Another object is to provide a method whereby the residence time in the heating zone and the temperature of the heating zone may be decreased to prevent undesirable side reactions from taking place. Still other objects are to provide cracking promoters which

will allow greater yields and greater efficiencies to be obtained in the cracking of these olefins. Still other objects will be apparent as the description proceeds.

To further explain what is meant by a carbon-to-carbon bond in a position beta to double bond, the following discussion is intended to be illustrative and not restrictive of the scope of this invention. The particular materials which predominate when olefins are cracked depend largely upon the configuration of the particular olefin. By configuration is meant the location of the double bond and the location of the side group in chain, if any. It is believed that this best can be illustrated by the following discussion. When an olefin containing 6 carbon atoms with a side group, i.e. a methyl group, attached to the second carbon atom of the main or straight portion of the chain, and the double bond in the 2 position, such an olefin being 2-methyl pentene-2, is subjected to cracking conditions, the predominant products obtained are 2-methyl butadiene-1,3 (isoprene) which is a diolefin, and methane, a paraffin. On the other hand if a 6 carbon olefin such as 2-methyl pentene-1, which has the double bond in the 1 position and the methyl group in the 2 position, is cracked, it will yield as predominant products two other olefins, isobutylene and ethylene. When still another isomeric hexene such as 4-methyl pentene-1 is cracked, two moles of propylene are formed. These differences in products obtained, when different isomeric forms of olefins containing the same number of carbon atoms are cracked, are due to the fact that olefins crack at the position beta to the double bond. That is to say, the carbon-carbon bond which is two carbon atoms removed from the double bond, is the carbon-to-carbon bond at which the scission occurs. There are certain olefins which do not contain in their molecular make-up a carbon-carbon bond in the position beta to the double bond and, therefore, do not undergo the same reactions when subjected to thermal decomposition conditions. These olefins are ethylene, propylene, butene-2, isobutene, 2-methyl butene-2, and 2,3-dimethyl butene-2, and are usually referred to as refractory olefins. Since these olefins do not undergo similar chain scission as do olefins which contain in their molecule a carbon-to-carbon bond in the beta position to the double bond, these refractory olefins are not considered to be within the scope of the olefins which are to be cracked in accordance with this invention.

It has been found that the objects of this invention are accomplished by subjecting olefins which have in their molecules a carbon-carbon bond which is in a position beta to the double bond to conditions of temperature and suitable or sufficient to cleave the carbon-to-carbon bond in the position beta to the double bond while in the presence of a promotor which comprises a mixture of bromine and at least one aromatic hydrocarbon selected from the group consisting of benzene, toluene and xylene.

The practice of this invention may be carried out in any conventional manner which is usually employed in the thermal cracking of olefins.

Generally, the conditions which may be employed in the practice of this invention may vary widely, for instance the cracking temperature may vary broadly from about 400° C. to about 900° C. However, more preferred cracking temperatures are from about 600° C. to about 750° C. The time in which the olefins are in the cracking zone may range broadly from about 0.001 to about 3.0 seconds. However, it is more preferable to employ times varying from about 0.05 to about 0.5 second. These times which are referred to are usually called residence times and are defined as the time required for one molecule of gas whether it be pure olefin or in mixture with the diluents to pass through the cracking zone.

As was stated above, generally olefins are cracked

either as pure hydrocarbons or as mixtures with other diluent gases. These diluent gases may be such materials as steam, carbon dioxide, hydrogen, paraffins, the refractory olefins, or any other inert gaseous substance which does not materially affect the cracking process or react with either the feed stock or products other than to act generally as a diluent. The ratio of this diluent gas may be widely varied depending on conditions, but it is usually employed in mol ratios of from 0.5/1 mole of diluent per mol of olefin to 15/1. If more than about 15/1 mol ratio is employed, the process tends to become uneconomical. Therefore, it is preferred to use a diluent to olefin mol ratio ranging from about 2/1 to about 4/1.

The pressure employed in the cracking zone may be varied from a low of 10 milliliters of mercury to 500 pounds per square inch gauge or even higher. However, it is usually preferred that the pressure range from about atmospheric to about 100 p.s.i. with about 1-2 atms. being preferred.

As was stated before, the activator or promoter employed in this invention to promote the cracking of olefins is a mixture of bromine and hydrocarbons selected from the group consisting of benzene, toluene and xylene and/or mixtures thereof. The bromine component of this promoter may be supplied either in gasous form or as a liquid under pressure. In addition to bromine itself any organic or inorganic bromine containing compound may be employed. Representative of such compounds are ammonium bromide and hydrogen bromide. The promoter may be added to the feed stock in various ways, however, it is usually found convenient to dissolve these materials in the olefin to be cracked. Other methods which may be employed are to feed the promoter mixture or even the promoter components separately into the cracking furnace along with the olefin and diluent, if any are being used.

The amount of promoter employed in the practice of this invention has not been found to be too critical. Of course, sufficient promoter should be employed to cause an effect and for the sake of economy no more promoter should be employed than is necessary. Generally, it has been the practice to employ at least 2.0 mol percent of promoter calculated as the bromine component. Usually, at least 2.0 mol percent of the hydrocarbon component of the promoter is used. The ratio of the hydrocarbon component of the promoter to the bromine component may vary widely and has not been found to be critical. A ratio of from about 1/1 to about 20/1 is usually employed. Also it has been found that little, if any, further improvement is obtained when more than 50 mol percent of the bromine component is employed. (All mol percentage calculations are based on the total mols of the olefin to be cracked.)

The practice of this invention is illustrated by the following experiments which are to be interpreted as

Exp. No.	Time	Temperature	Promoters	Yield	Efficiency
1	.15	675	None	17.3	69.0
2	.15	675	Tol. 4.8	17.9	69.5
3	.15	675	Tol. 9.1	15.2	69.7
4	.15	675	Tol. 16.7	12.2	65.9
5	.16	677	HBr 5.0	40.6	63.5
6	.14	676	Tol. 4.8, HBr 5.7	38.4	73.4
7	.15	676	Tol. 9.1, HBr 5.6	38.2	75.9
8	.16	675	Tol. 16.7, HBr 5.0	40.2	78.9
9	.15	675	Tol. 28.6, HBr 5.4	32.8	76.3
10	.15	675	Ben. 9.1, HBr 5.5	37.1	73.4

Tol.=Toluene.

Ben.=Benzene.

HBr=Hydrogen Bromide.

representative rather than restrictive of the scope of this invention. The results and conditions of the cracking experiments are reported in table form.

All of the cracking experiments were performed in a reactor assembly consisting of a "hairpin" coil prepared from $\frac{1}{4}$ -inch O.D. 316 stainless steel tubing. This coil reactor was immersed in a bed of fluidized heat transfer

70 From the above example it can be readily seen that the catalyst of this invention as exemplified by Runs 5 through 11 show a distinct improvement over hydrogen bromide alone (Run 5) and toluene alone (Runs 2, 3 and 4), as well as true thermal cracking (Run 1). Other similar results may be obtained when the general techniques of these examples and the other specific condi-

5 powder which was microspheroidal silica-alumina cracking catalyst. The heat transfer powder was heated both by electrical resistance heaters and by combusting a natural gas flame in the fluidized powder bed. The temperature gradient from top to bottom of the bed was never more than 5 to 6° C. and the gradient from the fluidized bed to the tube walls was about 5-6° C. The temperatures within the fluidized bed were measured by conventional thermocouple techniques as were the temperatures within the cracking zone. The procedure employed was to bring the heat transfer powder up to about 500° C. employing the electrical resistance heaters while fluidizing the heat transfer powder with air. Then the natural gas burner was employed to bring the heat transfer powder up to the desired cracking or operating temperature. When toluene and benzene was used in these experiments, it was added to the olefin feed stream. The bromine and/or hydrogen bromide were added separately to the cracking reactor. The water and the olefin feed stream were pumped at the proper rates necessary to produce the H_2O /hydrocarbon ratio desired and to give the desired residence time of the materials in the cracking zone or cracking reactor. When all variables had been adjusted to give the desired operating conditions the products resulting from the cracking operation were collected by means of cooled receivers, if liquid, and were metered at atmospheric and room temperature conditions, if gas. The products were analyzed for content and yields by conventional analytical methods. Conventional recycle techniques were employed to obtain the ultimate yield.

45 The results of each of the experiments in the following examples as well as the operating conditions are reported in tables below. Column 1 is the experiment number; column 2 is the residence time in seconds; column 3 is the temperature employed in the cracking operation in degrees centigrade; column 4 is the material employed as the particular cracking promoter with the amount employed in mol percent based on the olefin to be cracked (where no promoter was employed this column lists "none"); column 5 is the mol percent yield of isoprene per pass based on the 3-methyl pentene-2 charged; column 6 is the reaction efficiency or ultimate yield and is the amount of isoprene obtained based on the 3-methyl pentene-2 charged using conventional recycle techniques.

EXAMPLE

50 In this example 3-methyl-2-pentene was the olefin employed. A diluent, steam, was employed at a mol ratio of approximately 3.2/1, steam to hydrocarbon. In these experiments No. 1 illustrates the effect of true thermo cracking; 2, 3 and 4 illustrate the effect of toluene alone; 5 illustrates the use of hydrobromide alone; experiments 6-11 illustrate the practice of this invention and the improvement obtained thereby.

tions mentioned elsewhere in this application are applied to other olefins.

The list of olefins set forth below is representative of the olefins, the cracking of which may be enhanced by the promoter of this invention.

Representative among the olefins which will decompose to form predominantly butadiene-1,3 when cracked in accordance with the practice of this invention are pentene-2; hexene-2; 3-methyl pentene-1; cyclohexene; 3-methyl butene-1; 2-heptene; 3-methyl hexene-1; 5-methyl hexene-2; 2-octene; 5-methyl heptene-2; 3,5-dimethyl hexene-1; 3,4,4-trimethyl pentene-1; 6-methyl heptene-2; nonene-2; and 3-methyl octene-1.

Representative among the olefins which will decompose to form predominantly 2-methyl butadiene-1,3 or isoprene when cracked in accordance with the practice of this invention are 2-methyl pentene-2; 3-methyl pentene-2; 2-ethyl butene-1; 3,3-dimethyl butene-1; 2,3-dimethyl butene-1; 2-methyl hexene-2; 3-methyl hexene-2; 2-ethyl pentene-1; 2,3-dimethyl pentene-1; and 3,3-dimethyl pentene-1.

Representative among the olefins which will decompose to form predominantly 2-ethyl butadiene-1,3 when cracked in accordance with the practice of this invention are 3-ethyl pentene-2; 2-ethyl pentene-2 and 3-ethyl hexene-2.

Representative among the olefins which will decompose to form predominantly 2,3-dimethyl butadiene-1,3 when cracked in accordance with the practice of this invention are 2,3-dimethyl pentene-2; 3-methyl-2-ethyl butene-1; 2,3,3-trimethyl butene-1; 2-isopropyl pentene-1; 2,3,3-trimethyl pentene-1; and 2,3-dimethyl heptene-2.

Representative among the olefins which will decompose to form predominantly 3-methyl pentadiene-1,3 when cracked in accordance with the practice of this invention are 3-methyl heptene-3; 3,4-dimethyl hexene-2; and 3,6-dimethyl heptene-3.

Representative among the olefins which will decompose to form predominantly 2-methyl pentadiene-1,3 and 4-methyl pentadiene-1,3 when cracked according to the practice of this invention are 2,4-dimethyl pentene-2; 2-methyl heptene-3; 4,4-dimethyl hexene-2; 2-propyl pentene-2; 2-methyl-3-ethyl pentene-1; 2,6-dimethyl heptene-3 and 2-propyl hexene-1.

Representative among the olefins which will decompose to form predominantly piperylenes when cracked in accordance with the practice of this invention are hexene-3; 4-methyl pentene-2; heptene-3; 4-methyl hexene-2; octene-3; 4-methyl heptene-2; 6-methyl heptene-3; 3-ethyl hexene-1; 4-methyl-3-ethyl pentene-2; 4,5-dimethyl heptene-2; and 4,5,5-trimethyl hexene-2.

While certain representative embodiments and details have been shown for the purpose of illustrating the invention, it will be apparent to those skilled in this art that various changes and modifications may be made therein without departing from the spirit or scope of the invention.

What is claimed is:

1. A promoted pyrolysis process which comprises providing a mixture of (1) at least one olefin selected from the group consisting of pentene-2, hexene-2, 3-ethyl pentene-2; 2-ethyl pentene-2; 3-ethyl hexene-2; hexene-3; 4-methyl pentene-2; heptene-3; 4-methyl hexene-2; 2,3-dimethyl pentene-2; 3-methyl-2-ethyl butene-1; 2,3-

dimethyl heptene-2; 3,4-dimethyl hexene-2; 3-methyl heptene-3; 2,4-dimethyl pentene-2; 2-methyl heptene-3; 2-propyl pentene-2; 2-methyl pentene-2; 3-methyl pentene-2; 2-ethyl butene-1; 2,3-dimethyl butene-1; 2-methyl hexene-2 and 3-methyl hexene-2 characterized in that they contain in their molecule a carbon to carbon single bond in a position beta to the double bond and (2) a cracking promoter consisting essentially of a mixture of (a) at least 2 and not more than 50 mole percent of a bromine containing compound selected from the group consisting of hydrogen bromide and ammonium bromide based on the olefin and (b) at least 2 mole percent of at least one hydrocarbon selected from the group consisting of benzene, toluene and xylene based on the olefin, the mole ratio of (b) to (a) ranging from 1 to 1 to about 20 to 1, and cleaving these carbon-to-carbon single bonds, which are in a position beta to the double bond of said olefins, by subjecting said mixture to temperatures ranging from about 600° C. to about 750° C. for periods of time ranging from about 0.05 to about 0.5 second.

2. A process according to claim 1 in which the bromine containing compound is hydrogen bromide.

3. A process according to claim 1 in which the olefin is at least one selected from the group of pentene-2 and hexene-2, thereby producing a predominance of butadiene-1,3.

4. A process according to claim 1 in which the olefin is at least one selected from the group of 3-ethyl pentene-2; 2-ethyl pentene-2 and 3-ethyl hexene-2, thereby producing a predominance of 2-ethyl butadiene-1,3.

5. A process according to claim 1 in which the olefin is at least one selected from the group of hexene-3; 4-methyl pentene-2; heptene-3 and 4-methyl hexene-2, thereby producing a predominance of piperylene.

6. A process according to claim 1 in which the olefin is at least one selected from the group of 2,3-dimethyl pentene-2; 3-methyl-2-ethyl butene-1 and 2,3-dimethyl heptene-2, thereby producing a predominance of 2,3-dimethyl butadiene-1,3.

7. A process according to claim 1 in which the olefin is at least one selected from the group of 3,4-dimethyl hexene-2 and 3-methyl heptene-3, thereby producing a predominance of 2-methyl pentadiene-1,3.

8. A process according to claim 1 in which the olefin is at least one selected from the group of 2,4-dimethyl pentene-2; 2-methyl heptene-3 and 2-propyl pentene-2, thereby producing a predominance of 2-methyl pentadiene-1,3 and 4-methyl pentadiene-1,3.

9. A process according to claim 1 in which the olefin is at least one selected from the group of 2-methyl pentene-2; 3-methyl pentene-2; 2-ethyl butene-1; 2,3-dimethyl butene-1; 2-methyl hexene-2 and 3-methyl hexene-2, thereby producing a predominance of isoprene.

10. A process according to claim 9 in which the bromine containing compound is hydrogen bromide.
